UNITED STATES PATENT OFFICE

ALBERT EDGAR KNOWLES, OF HESWALL, ENGLAND

GAS WASHER FOR ELECTROLYTIC APPARATUS

Application filed October 15, 1926, Serial No. 141,777, and in Great Britain October 19, 1925.

This invention relates to means for automatically controlling the level of the liquid in electrolytic cells and for washing the gases evolved therein, and refers particularly to means in which water or other fluid is fed into one or more chambers in which gas or gases evolved from the cells are caused to bubble through the fluid, which then passes into a further chamber containing a float 10 operating a valve which controls the supply of fluid to the initial chamber or chambers, the fluid being fed from the float chamber to the cells to maintain the level of the electrolyte therein.

15 The principal object of my invention is to provide improved means for bringing the feed water or other liquid and the gases evolved from the cells into such intimate contact that all electrolyte present in the gases 20 is removed and the gases are delivered to pumps or gas-holders in a dry and pure condition.

Further objects of my invention are to provide detail improvements in the apparatus with the object of increasing its all-round 25 efficiency in practice.

My invention comprises an improved apparatus of the type set forth for maintaining the liquid level in electrolytic cells and washing 30 the gas or gases evolved therein, in which gas from the cells is caused to pass downwardly through vertical tubes in the washing chamber which have their lower ends immersed below the surface of the liquid 35 therein, and the gas bubbles upwardly through a perforated plate on its way to the gas outlet.

To prevent any undue pressure being generated 40 in the washing chamber a blow-off liquid seal is preferably provided on the top of the chamber, the depth of the seal being adjustable to suit different conditions.

An embodiment of the invention, suitable 45 for employment in a plant for the decomposition of water and the production of hydrogen and oxygen, is illustrated in the appended drawings.

Figure 1 is a part sectional elevation of 50 this apparatus.

Figure 2 is a sectional plan on line 2-2 of Fig. 1.

Figure 3 is a plan of a seal chamber which may be employed on each tank.

Figure 4 is a detail of the control valve 55 shown in section.

Figure 5 is a perspective view of a suitable form of bracket for supporting the control valve.

In this arrangement, two tanks *a*, *b*, are 60 employed for each feed water unit, and into these two tanks the two gases set free by the decomposition of the water are led respectively. The gas inlets to the tanks *a*, *b*, are marked *c* and *d*, and two are shown 65 on each tank, but this is merely because the particular tanks illustrated were intended for washing the gases and controlling the make-up water for two groups or rows of cells. In this case, of the two gas collecting 70 pipes or mains on each group of cells, naturally the pipe or main conveying hydrogen will go to one tank, and the one containing oxygen to the other tank. The top of each tank is shown as a flanged bell, easily removable from the flanges *e* of the main body of the tank. At the top of the main body 75 of the tank is secured a tube plate *f*, through which a number of open-ended tubes *g* depend, and below this tube plate, preferably 80 just above the lower ends of the tubes *g*, a second plate *h* is arranged. This plate *h* may be secured to the tubes *g* by spot welding, or like operation, so that the entire nest 85 of tubes is removable from the tank if desired. In any case, the plate *h* has a number of perforations *j* through it in the spaces between the apertures through which the mouths of the tubes pass. A gas outlet *k* from each tank is provided in the middle 90 part between the tube plates *f* and *h*.

The control chamber *m* may conveniently be disposed between, and partly below, the two washing tanks disposed side by side, so that the connections are as short as possible. 95

The liquid outlets *n*, *o* from the tanks *a*, *b* to the control chamber *m* are arranged between the lower mouths of the tubes *g*, and the gas passages *k*, at a height above the mouths of the tubes *g* determined by a suit- 100

able liquid seal on the gas. If desired the outlets could be made adjustable to permit of regulation of the seal, but it is preferred to set them when the tanks are made.

5 A water inlet *p* is led down into the space below the perforated plate *h* in each tank, preferably being arranged through the side wall opposite to the gas passage with a depending pipe inside the tank carried through 10 the perforated plate.

10 Outside the tank a cup *q* receives the clean water from the control valve *r* Figure 3, actuated by the float *s* in the control chamber *m*.

15 Gas is led into the top of each washing tank *a*, *b*, and passes down the tubes *g* below the water level and bubbles up through the water and through the perforated tube plate *h* into the middle compartment, and so 20 to the gas passage *k* in the side wall thereof.

It is thus washed very thoroughly by the feed water as a very intimate contact between the gas and the water is ensured as the gas passes the perforated plate *h* below 25 the liquid level. The feed water is led to the valve *r* through pipe *U* above the control tank *m*, and as the valve is opened by a fall of the float *s*, is introduced into each washing tank, while the feed water and washed 30 out electrolyte from the two tanks is led out at *n*, *o*, and down into the bottom portion of the control tank *m* from which, at the level of the electrolyte in the cells, a feed outlet *t* to the cells is arranged.

35 Particular constructional forms of certain parts, notably the valve, a supporting bracket for the valve, and a blow off seal for the tanks *a*, *b* which offer advantages in use are illustrated in the drawings.

40 As shown at Figure 4 the float valve *r* comprises a face valve *u* for closing an aperture in a removable disc *v* screwed into the opening of a flanged union member *w*.

Upon a lower shoulder of the valve spindle 45 is a hollow piston valve *x* with ports in its walls opposite the branches *y* leading to the cups *q* seen in Figure 1. The face valve places the valve chamber in communication with, or obturates, the passage from a source 50 of supply such as the pipe *U*, and the piston valve ensures an equal flow from the valve chamber to the branches *y* and cups *q*.

A bracket for supporting the valve is shown in Figure 5, which can readily be 55 made from bent up plate or sheet metal blank. The blank *z* is shown in dotted lines and is bent to the shape shown in full lines. The bottom edge of the main portion 1 and of the side flanges 2, can be welded or otherwise secured to the top of the control chamber *m*, and the forked part 3 of the bracket 60 embraces the valve body *r* below the flanged part *w*. The valve can then be secured to the bracket by the same bolts as serve for 65 connecting the supply pipe to the flange *w*,

and for this purpose bolt holes 4 and notches 5 are formed in the bracket 3. The side flanges 2 are stiffeners for the bracket, and may be welded at the top edge to the forked part 3; they are notched as at 6 to pass the 70 side branches *y* of the valve body. 7 is an aperture for a knuckle mounting of the lever 8, Figure 2, on which the valve spindle is mounted and from the remote end of which depends the float *s*.

75 The particular blow off seal for the gas provided on the top of the tanks *a* and *b* comprises a stand pipe 9 around which is secured a liquid vessel 10 in which a bell 11 over the stand pipe is sealed. Screw pins 80 12 are secured in lugs 13, Figure 3, projecting from the top of the bell, and are passed through eyes 14 welded on the liquid vessel. By releasing one of the nuts 15 which are threaded on the bolts above 85 and below the eye and screwing the other nut against the fixed eye, the bolt is traversed, and, by adjusting all the bolts in this manner, the bell 11 is raised or lowered to vary the head of liquid seal between 90 the lower edge of the bell and the liquid overflow 16 in the liquid vessel 10.

I claim:

1. Means for washing the gas evolved from an electrolytic cell and containing electrolyte in suspension, comprising a closed liquid-containing chamber, automatic valve-controlled means for feeding liquid into the chamber, automatic overflow means for withdrawing liquid from the chamber to maintain a constant head therein, a removable upper part to said chamber, two spaced tube plates arranged transversely in said chamber, tubes connecting said plates, a gas inlet leading into said removable upper part, perforations in the lower tube plate between the tubes, and a gas outlet from the chamber between the tube plates. 100

2. Means for washing the gas evolved from an electrolytic cell and containing electrolyte in suspension, comprising a closed liquid-containing chamber, automatic valve-controlled means for feeding liquid into the chamber, automatic overflow means for withdrawing liquid from the chamber to 105 maintain a constant head therein, a removable upper part to said chamber, two spaced tube plates arranged transversely in said chamber, tubes connecting said plates, a gas inlet leading into said removable upper part, perforations in the lower tube plate between the tubes, and a gas outlet from the chamber between the tube plates. 110

3. Means for washing the gas evolved from an electrolytic cell and containing electrolyte in suspension, comprising a closed liquid-containing chamber, automatic 115

4. Means for washing the gas evolved from an electrolytic cell and containing electrolyte in suspension, comprising a closed liquid-containing chamber, automatic 120

5. Means for washing the gas evolved from an electrolytic cell and containing electrolyte in suspension, comprising a closed liquid-containing chamber, automatic 125

valve-controlled means for feeding liquid into the chamber, automatic overflow means for withdrawing liquid from the chamber to maintain a constant head therein, a removable upper part to said chamber, a blow off liquid gas seal on said part, means for adjusting the effective head of liquid in the seal, two spaced tube plates arranged transversely in said chamber, tubes connecting said plates, a gas inlet leading into said removable upper part, perforations in the lower tube plate between the tubes, and a gas outlet from the chamber between the tube plates.

15 In testimony whereof I affix my signature.

ALBERT EDGAR KNOWLES.
